F. E. LEVANSELER,
SUPPORT FOR HINGED COVERS OR MEMBERS,
APPLICATION FILED APR. 30, 1919.

1,324,601.

Patented Dec. 9, 1919.

UNITED STATES PATENT OFFICE.

FRANK E. LEVANSELER, OF CHICAGO, ILLINOIS.

SUPPORT FOR HINGED COVERS OR MEMBERS.

1,324,601.

Specification of Letters Patent.

Patented Dec. 9, 1919.

Application filed April 30, 1919. Serial No. 293,680.

To all whom it may concern:

Be it known that I, FRANK E. LEVANSELER, a citizen of the United States, residing at the city of Chicago, in the county of Cook and State of Illinois, have invented certain new and useful Improvements in Supports for Hinged Covers or Members, of which the following is a specification.

This invention, like the one set forth in an application, Serial Number 288,102, filed by me on the 7th day of April, 1919, relates to certain improvements in means for supporting the hinged lids or covers of phonographs, graphophones, desks, trunks, boxes, pianos and the like, when raised or turned on their hinges, to any desired elevation or angle, in such a manner that the supporting action or operation of the device will be automatic, and of such a character as to securely hold the lids, covers or members in their tilted or raised position, against accidental lowering or falling of the same, yet, so that by the proper manipulation of the cover or member, and by applying slight downward or upward pressure thereto, it can be easily lowered or raised, in which position it will remain until again moved by pressure in the desired direction.

The principal object of the invention is to provide a support of the above named general character, which shall be extremely simple and inexpensive in construction, strong, durable and effective in operation, with its parts so made and arranged that they can be easily applied or attached to the article and its cover, and when in use, will be concealed or protected, when the cover or member is closed. Other objects and advantages of the invention will be disclosed in the following description and explanation.

In the accompanying drawing, which serves to illustrate an embodiment of the invention—

Figure 1 is a vertical sectional view of a portion of a casing such as a phonograph or graphophone case or box or trunk with its lid closed, showing one form of the support in position ready for use;

Fig. 2 is a similar view of like parts showing the cover or lid raised or tilted and illustrating the position the parts of the support will assume;

Fig. 3 is a sectional view taken on line 3—3 of Fig. 1 looking in the direction indicated by the arrows, showing the spring used for locking or retaining the support

ing link and lever in their lowered positions, and

Fig. 4 is a detached view in side elevation of a fragment of the support illustrating a modification therein and showing by continuous lines about the position the parts of the device will assume when the lid or cover is raised, and by dotted lines the position of said parts when the cover and the parts are in their lowered position and retained in such position by the spring employed for said purpose.

Corresponding numerals of reference refer to like parts throughout the different views of the drawing.

The reference numeral 7 designates one of the walls, for instance, the rear wall of the box or casing, to which the lid, hinged member or cover 8 is secured at one of its edges by means of hinges 9 of the ordinary or any preferred construction. As is well known the lids or covers 8 are usually provided at their perimeters with downwardly extended and outwardly inclined walls 10, the inclination of which walls vary in different structures, that is to say, some of them are extended at greater angles than others; to provide means for attaching the support to the walls 10 of the lids or covers no matter what the inclination thereof may be, a plate 11 having a hook 12 on its lower portion is secured to one of the walls 10 of the lid, usually one of the side or end walls thereof, and a member 13 having an opening 14 to receive said hook is placed between the wall and hook so that the said member will extend vertically from the latter. To the lower portion of the member 13 one end of a link 15 is pivotally secured, the other end of which is similarly secured to a link or lever 16, which is provided with a series of spaced apart openings 17 arranged in a longitudinal row on the link or lever 16, as is clearly shown in the drawing. The end of the link or lever 16 opposite the end thereof connected to the link 15 is pivotally secured to a support 18, which, in the present instance, is shown as being a bar fastened by means of screws 19 to the side or end wall 20 of the box or casing and located in a downwardly inclined position from the front portion of the casing toward the rear wall thereof, as shown in Figs. 1 and 2 of the drawing. This bar or support is by preference provided with an inwardly extended off-set 21, to which the lower end of

100
105
110

the link or lever 16 is pivoted, thus holding the said link or lever at a distance from the wall 20 of the casing to permit of its free movement without contacting with said wall, and also in such a way that the spring 22 which actuates said link or lever from contacting with or marring said wall. The upper end of the bar or support 18 is provided with an inwardly extended bracket or 10 arm 23, to which is secured one end of a leaf spring 24, which is substantially U-shaped, as shown, and is disposed across the inner surface of the bar 18. Mounted on the bar 18 near the spring 24 is a substantially U-shaped guide member 25 for the lever or link 16, which member has its free end outward as at 26 in Fig. 3 of the drawing, to facilitate the entrance of the link 16 between said portion and that part thereof 15 secured to the bar 18. Secured to the upper rear portion of the wall 20 of the casing is a plate 27, which has on its end adjacent to the bar 18 an inwardly extended apertured bracket 28, in which opening is threaded a screw hook 29, which hook engages one end 20 of the spring 22, the other end of which is provided with a hook 30 for detachably or 25 adjustably connecting it in the opening 17 of the lever or link 16, so as to regulate the tension of said spring, as may be required to counterbalance the weight of the lid, cover or hinged member. By the above mentioned arrangement of the spring 22, it is 30 obvious that if nice or fine adjustment of the tension of said spring is desired, this can be obtained by turning the nut 31 on the screw hook 29 in the proper direction, or if coarse or quick adjustment thereof is desired, the hook 30 on the spring 22 can be 35 moved from one of the openings 17 in the lever or link 16 and placed in another one of said openings.

In Fig. 4 of the drawing, is shown a modification in the construction of the support, 40 which consists in reversing the position of the support 18 so that the guide member 25 and retaining or locking spring 24 will be located near the end of the link or lever 16, which is pivoted to the support or bar 18, instead of at or near the juncture of said link 45 or lever with the link 15, as in the first above described construction. In this modified form the link or lever 16 is provided with an extension 32, which projects from the fulcrum or pivot 33 which unites said 50 link or lever to the support 18 so that when the hinged member is lowered said extension will contact with the spring 24 and be held thereby in its lowered position, or that 55 shown by dotted lines in Fig. 4 of the drawing. It is further obvious that in this modified construction the free ends of the spring 24 and guide member 25 will be presented 60 downwardly instead of upwardly as in the other construction. It is further apparent 65

that the spring 24 and guide member 25 may be suitably mounted on the wall 20 of the casing at proper points thereon for coaction with the link or lever 16 without using the bar 18, and it is further manifest that the 70 pivot 33 of the lever or link 16 can be mounted on a suitable support separate from the said bar.

Having thus fully described my invention what I claim as new and desire to secure by Letters Patent is—

1. The combination with a hinged cover or member, of a link pivotally connected at one of its ends thereto at a suitable distance from its hinged portion, a spring-actuated 80 lever pivotally connected at one of its ends to the other end of the link and pivotally connected at its other end to a fixed support, and a spring extended across the path of the lever to engage and hold the same in its low- 85 ermost position.

2. The combination with a hinged cover or member, of a link pivotally connected at one of its ends thereto at a suitable distance from its hinged portion, a lever having 90 spaced apart openings arranged in a longitudinal row therein, said lever being pivotally connected at one of its ends to the said link and at its other end to a fixed support, the said openings being located between the 95 pivots of the lever, and a spring connected at one of its ends to the lever between the pivots thereof and at its other end to a suitable fixed support.

3. The combination with a hinged cover 100 or member, of a link pivotally connected at one of its ends thereto at a suitable distance from its hinged portion, a suitably fulcrumed lever pivotally connected at one of its ends to the other end of the link, a spring 105 adjustably connected at one of its ends to the lever between the pivots thereof, adjustable means connected to the other end of said spring and suitably supported, and a spring extended across the path of the lever to engage and hold the same in its lowermost position.

4. The combination with a hinged cover or member, of a link pivotally connected at one of its ends thereto at a suitable distance 110 from its hinged portion, a suitably fulcrumed lever having spaced apart openings arranged longitudinally therein between its pivots and pivotally connected at one of its ends to the other end of the link, a spring 115 having means at one of its ends to adjustably engage said openings in said lever, a screw hook adjustably mounted and engaging the other end of said spring, and a spring extended across the path of the lever 120 to engage and hold the same in its lowermost position.

5. The combination with a hinged cover or member, of a link pivotally connected at one of its ends thereto at a suitable distance 125

from its hinged portion, a suitably fulcrumed lever having spaced apart openings arranged longitudinally therein between its pivots and pivotally connected at one of its ends to the other end of the link, a spring detachably connected at one of its ends in one of the openings of said lever, means con-

nected to the other end of said spring for regulating the tension thereof, and a spring extended across the path of the lever near 10 the end thereof connected to the link and adapted to engage and hold the lever and link in their lowermost positions.

FRANK E. LEVANSELER.
